UNITED STATES PATENT OFFICE.

HARRY COMSTOCK, OF FULTON, NEW YORK.

PIPE-CUTTER.

SPECIFICATION forming part of Letters Patent No. 426,171, dated April 22, 1890.

Application filed December 19, 1890. Serial No. 334,270. (No model.)

To all whom it may concern:

Be it known that I, HARRY COMSTOCK, a citizen of the United States, residing at Fulton, in the county of Oswego and State of New York, have invented new and useful Improvements in Pipe-Cutters, of which the following is a specification.

My invention relates to certain improvements in pipe-cutters for cutting metallic pipes, and the purpose thereof is to provide novel means by which a pipe is channeled to guide the cutters and the burr raised by the cutters is wholly removed, leaving the end of the pipe perfectly smooth, with a uniform 15 surface and diameter and a beveled edge. It is my purpose, also, to provide a tool of this character in which the fixed jaw shall have a guiding edge or rib coinciding with the path of the cutting-disks, the latter being pivoted 20 in or upon the sliding head which moves upon the cutter-stock.

The invention consists in the novel features of construction and new combinations of parts which are fully described hereinafter, and then more definitely pointed out in 25 the claims following this specification.

To enable others skilled in the art to make and use my said invention, I will now describe the same fully and in detail, reference being had to the accompanying drawings, in 30 which—

Figure 1 is a perspective view of a pipe-cutter in which my invention is embodied. Fig. 2 is a detail perspective of the fixed reducing and burnishing block provided with a guiding rib or edge. Fig. 3 is a vertical section of the sliding head with the pivotally-attached cutters mounted thereon. Fig. 4 is a diagram showing the action of the cutters and the reducing-block upon a tube or pipe. Figs. 5 and 6 are similar views showing the action upon pipes of different forms 40 of cutters heretofore used.

In the said drawings, the reference-number 45 1 denotes the cutter-stock, consisting of a strong rectangular metallic bar having one extremity curved to form a fixed jaw 2, which supports the pipe. Upon the straight portion of the stock is mounted the sliding head 50 3, which is provided with a rectangular opening to receive the stock. Its adjustment is effected by means of a screw 4, having a thread

of low pitch, said screw being tapped through a lug 5 on the stock.

Within the curve of the fixed jaw I mount 55 a reducing and burnishing block 6, segmental in shape and having a guiding edge or rib 7 rising from its central longitudinal line and coextensive with the block. Upon each side of this edge or rib I may and prefer to form 60 teeth 8, which may be either transverse corrugations or inclined with reference to the rib 7, or they may consist of teeth similar to those employed upon a file. This block 6 is formed of steel properly hardened, and is inserted in a recess in the curved end 2 of the stock.

The cutting-disks 9 are of the usual form, their edges being turned or ground to give the required shape. These cutters are two in 70 number, and they are journaled in the bifurcated extremities of the U-shaped segmental plate or carrier 10, which is centrally pivoted between its ends upon a pin 12, inserted in a forked angle 13 of the sliding head. 75

The operation of the tool is evident. The pipe being placed in the fixed jaw and resting upon the block, the screw 4 is turned until the cutters are brought up to the pipe. The tool is then revolved or drawn around 80 the pipe, the rib or edge 7 cutting a guiding-channel in which the cutter-disks travel. The pipe now lies flat upon the concave face of the reducing-block, and as it turns thereon the burr which is thrown up by the cutters is 85 immediately removed, the teeth 8 not only reducing the burr, but burnishing the surface of the pipe, leaving it of substantially the uniform shape and diameter shown in Fig. 3, with the edge beveled at an angle corresponding 90 with the angle of the cutting-disks.

I may omit the teeth 8 upon the block entirely, in which case its flat surfaces will act upon each side of the central rib as a swage, reducing the burr and preserving a smooth 95 and uniform cylindrical surface.

My improved tool is particularly useful in cutting what is known as "irregular piping"—that is, pipes which are not uniformly circular in cross-section, but are in a measure oval 100 or elliptical or otherwise irregular as regards a true circle in cross-section. In cutting such piping a rigid cutter breaks through, because the cutter in operating on an irregular curve

jumps from one high point to another; but with my improved segmental plate or frame pivoted to rock and carrying a pair of rotary cutters the objection mentioned is entirely avoided, for the rocking centrally-pivoted segmental frame causes the cutters to follow every irregularity of pipe-surface, and while one rotary cutter is at a high point of the piping the other rotary cutter is or may be at a low point of the same. As the pressure from the adjusting-screw is equally distributed on the two cutters by reason of the rocking frame whatever its position, the two cutters are made co-ordinate or equilibrated in action, thereby equally cutting the high and low places of the pipe at the same instant, or, in other words, cutting as much in the low place as in the high place.

In my improved tool the reducing and burnishing block is a rigid or immovable fixture during the pipe-cutting operation, and I have found that such rigid and immovable burnishing-block removes the burr effectually to produce a fine smooth end, and is superior to a revolving burr-removing wheel carried by an adjustable slide, for I have found in practice that a rotating burnisher, by constantly rolling over the pipe, forms a scale and another or second burr. The rigid and immovable burnishing-block constructed and arranged according to my invention burnishes the two end surfaces of the piping perfectly smooth and bright and entirely avoids the formation of another burr. The burr formed by cutting a pipe is a solid bank or spun-up part of the metal, and to perfectly remove it and burnish the pipe end surfaces great friction is essential. A roller burnisher is inefficient, for it flattens the burr and forms another burr, whereas my burnisher, being rigid and immovable in operation, cuts and rubs the ends of the pipe down to the desired form, while the rib follows as a guide in the groove made by the cutters in the initial turn of the tool around the pipe.

What I claim is—

1. In a pipe-cutter, the combination, with a stock having a fixed jaw and a sliding head carrying cutting-disks, of a curved reducing and burnishing block fixed stationary in the fixed jaw and having a central curved channel-cutting rib, and a curved burr-removing face at each side of the rib, whereby a channel for guiding the cutting-disks is cut in the pipe and the burr raised by the disks is removed, substantially as described. 55

2. In a pipe-cutter, the combination, with a stock having a fixed jaw and a sliding head carrying cutting-disks, of a segmental reducing and burnishing block fixed in a stationary position in the fixed jaw and having a central segmental channel-cutting rib and a segmental burr-removing face at each side of the rib, substantially as described. 60

3. In a pipe-cutter, the combination, with a stock having a fixed jaw and a sliding head carrying cutting-disks, of a reducing and burnishing block fixed stationary in the fixed jaw and having a central segmental channel-cutting rib and a segmental burr-removing toothed face at each side of the rib, substantially as described. 65 70

4. In a pipe-cutter, the combination, with a stock having a fixed jaw and a sliding head thereon, of a segmental rocking plate pivoted centrally between its ends to the head and carrying at each extremity a rotating cutting-disk, and a reducing and burnishing block fixed in a stationary position on the fixed jaw and having a central longitudinal channel-cutting rib and a flat burr-removing face at each side of the rib, substantially as described. 75 80

In testimony whereof I have affixed my signature in presence of two witnesses.

HARRY COMSTOCK.
